JENS ORTEN BOVING, OF LONDON, ENGLAND.

HYDRAULIC GOVERNOR FOR ENGINES, TURBINES, AND THE LIKE.

Application filed February 1, 1922. Serial No. 533,336.

This invention relates to an improved hydraulic governor for engines, turbines and the like prime movers.

The object of the invention is to provide a governor which shall be sufficiently sensitive to keep the speed variations of the prime mover within small limits, while providing sufficient force to overcome the frictional resistance of the control gear of the prime mover.

The invention consists in a governor comprising a hydraulic tachometer having a cylinder, piston, spring, and a centrifugal impeller driven by the prime mover, and a co-operating hydraulic relay or servomotor, the piston element of which operates the control gear of the prime mover and whose position of equilibrium in its cylinder is determined by the tachometer piston.

The invention also consists in a governor of the kind above defined in which the servomotor comprises a differential piston and cylinder, a pump which continually supplies liquid under pressure to the cylinder chamber of smaller effective piston area, an outlet passage from the cylinder chamber of larger effective piston area, and a constricted passage connecting the two said chambers; the opening to the outlet passage being controlled by the pistons of the tachometer and servomotor.

The various parts are connected in such manner that when the tachometer piston has been moved a certain distance from its normal position due to a change of speed of the prime mover from its normal value, the piston element of the hydraulic relay is displaced from its normal position, thereby operating the control gear so as to bring the speed of the prime mover nearer to its normal value.

The oil is delivered direct from the pump to the cylinder chamber of smaller effective piston area, from which a passage, which may be throttled, communicates to the chamber of larger effective piston area. When the prime mover is running steadily the differential piston of the servomotor and the tachometer piston are at rest, the outlet opening for the oil being of such amount that the reduction of pressure of the oil in flowing through the constricted passage between the two cylinder chambers gives equal total pressures on the two opposite effective sides of the differential piston.

I append drawings diagrammatically illustrating my invention:

Figure 1 is a sectional view of a governor in which the outlet passage for the oil is through the differential piston;

Figure 2 is a sectional view of a governor in which the outlet passage for the oil is taken through the cylinder casting and the outlet is controlled by a piston valve;

Figure 3 shows a modification in which the outlet opening is controlled by a piston valve and a concentric sleeve.

In carrying the invention into effect in one form the tachometer comprises a centrifugal impeller 1 which is driven directly or indirectly by the prime mover, a cylinder 2 and piston 3. The impeller supplies oil or other liquid under pressure to the cylinder thereby tending to move the piston in one direction, the liquid pressure being counterbalanced by a spring 4, or by a spring and dead weights, in such manner that the piston moves a certain definite distance from its normal position when the speed of the prime mover changes to a definite value different from the normal value. The servomotor comprises a cylinder casing or the like having two coaxial bores of different diameters, two pistons, or a piston 5 and plunger 6, in fixed connection with each other forming a differential piston 7, which may be driven by the prime mover, supplying oil under pressure to the cylinder chamber 8 of smaller effective piston area. The differential piston is connected by suitable mechanism to the operating gear of the prime mover.

In one convenient form, Figure 1, the pistons of the tachometer and servomotor are arranged coaxial and vertical, the tachometer cylinder 2 being above the larger cylinder 9 of the servomotor and integral therewith. A piston rod 10 fixed to or integral with the tachometer piston 3 passes through a stuffing box in the cylinder casing and fits easily but practically fluid-tight in a central axial hole 11 bored through the differential piston of the servomotor.

When the prime mover is running steadily at normal speed the pistons of the tachometer and servomotor are at or near the middle positions of their respective strokes. The circular edge 12 of the lower end of the cylindrical surface of the tachometer piston rod is then slightly above the upper circular

edge 14 of the axial hole through the differential piston of the servomotor. This permits oil to escape through the said hole, reducing the intensity of pressure on the upper surface of the differential piston until the total downward pressure thereon is equal to the resultant upward pressure on the other surfaces of the differential piston. In this and other relative positions the tachometer piston rod and the differential piston co-operate to act as a valve, opening or closing the passage for the escape of oil. An adjustable screw throttle valve 13 is placed in the passage 15 between the two ends of the cylinder 9 to regulate the rate of flow of oil therethrough. The piston rod 10 is extended beyond the said circular edge 12 for the purpose of guiding it as it enters the hole 11 of the piston. The extension 20 may comprise a neck 16 of reduced diameter near the said circular edge, a cylindrical part 17 fitting the hole in the piston, and a tapered part 18; the said cylindrical and tapered parts being grooved 25 longitudinally as at 19 to provide oil passages.

The cylinder casing is supported on a pedestal 20. The pedestal supports a wiper shaft 21 which is oscillated by the axial movement of the differential piston and transmits that movement by suitable means to the operating gear of the prime mover. A sump or tank 22 on the pedestal collects the oil escaping through the differential piston, and supplies the oil pump 7 which is suitably mounted on the pedestal or attached to the servomotor cylinder casing.

The action of the governor is as follows: When the prime mover is running steadily at its normal speed the parts are in equilibrium as hereinbefore described. If, now, the speed of the prime mover increases, due to a reduction of the load, the tachometer piston and piston rod will be displaced into a new position of equilibrium. If the fluid presses on the upper side of the tachometer piston with sufficient force to overcome the upward pressure of the spring on the lower side thereof, as shown in the drawings, the said displacement will be downwards; the piston rod 10 enters the hole 11 of the differential piston and closes the oil passage therethrough. The oil being delivered by the pump 7 flows through the passage 15 and gradually forces the differential piston downwards until it comes to rest in such position that oil escapes through the central hole at the same rate as it is being supplied by the pump. If, now, the speed of the prime mover decreases, the tachometer piston and piston rod move upwards into a new position, the oil escapes more freely through the differential piston than it can pass the throttle

valve 13, the pressure on the upper surface of the differential piston is reduced, and the resultant oil pressure forces the differential piston upward until it comes to rest in proximity to the tachometer piston rod.

The modifications shown in Figures 2 and 3 act similarly. They differ from the arrangement shown in Figure 1 in that separate slide valve gear is provided to regulate the outlet opening, and a port from the cylinder chamber of larger effective piston area to the slide valve chamber serves both as outlet passage and constricted passage aforesaid. Incidentally, the stroke of the tachometer piston may be made less than that of the servomotor piston.

In Figure 2 a piston valve 25 controls the outlet opening and is connected to a lever 26 the two ends of which are moved by the pistons of the tachometer and servomotor respectively. In Figure 3 the piston 25 is coupled direct to the tachometer piston 3, and a concentric ported sleeve 26 is connected to the servomotor piston, and is slideable in the cylinder 27 coaxial with the tachometer cylinder 2. With this arrangement the tachometer spring 4 may be made long relative to the stroke of the tachometer piston, which in turn may be made small relative to that of the servomotor piston, thereby keeping the speed variation of the tachometer, and therefore also of the prime mover, within small limits.

Having now described my invention what I claim as new and desire to secure by Letters Patent is:—

1. A governor for prime movers comprising a hydraulic tachometer constituted by a cylinder, a piston, a spring and a centrifugal impeller driven by the prime mover, a cooperating hydraulic servomotor constituted by a differential piston and cylinder, a pump, a conduit between said pump and the cylinder space exposed to the smaller effective piston area, a constricted passage interconnecting the two cylinder spaces, and valve means associated with one of said pistons coacting with an outlet port associated with the other of said pistons to produce a variable outlet passage from the cylinder space exposed to the larger effective piston area.

2. A governor as claimed in claim 1, in which the cylinders and pistons of the tachometer and servomotor are coaxially disposed, the outlet passage comprising a coaxial hole through the differential piston of the servomotor and a rod attached to the piston of the tachometer being slideable therethrough for the purpose of controlling the amount of opening.

In testimony whereof I have signed my name to this specification.

JENS ORTEN BOVING.
